SOUND REPRODUCING APPARATUS

Frederick R. Marion, Floral Park, N. Y., assignor
to Electrical Research Products, Inc., New York,
N. Y., a corporation of Delaware

Application June 12, 1936, Serial No. 84,841

12 Claims. (Cl. 181—27)

This invention relates to sound reproducing apparatus and more particularly to acoustic transducers capable of distributing sound over a large space angle and adapted to have a plurality of acoustic devices coupled thereto.

One object of this invention is to distribute sound faithfully and with substantially uniform intensity throughout a large space angle.

Another object of this invention is to insure substantially uniform sound distribution throughout a desired space angle from a plurality of horns delivering sound from a plurality of receivers, in the event of failure of one of the receivers.

In one illustrative embodiment of this invention, a loud-speaker comprises a transducer including a plurality of groups of elongated flaring horns, horns of one group being interleaved with those of another. The horns are arranged side by side and in a number of equal rows, and are coupled to a pair of receivers for supplying sound energy. Preferably the horns have their outlets or mouths disposed in a plane.

In accordance with one feature of this invention the inlets or throats of each group of horns, for example of alternate horns in each of the rows are acoustically coupled. For example, the inlets of alternate horns may merge into a common sound duct or extend into a coupler member to which one of the receivers is coupled.

In accordance with another feature of this invention, the several horns are so designed that a smooth transition is obtained between the inlet of the coupler member and the throats of the horns associated therewith. For example, the horns may have rectangular mouths and the coupler member may have a circular inlet and may flare to a substantially square outlet. The horns are then flared so that they terminate in substantially square inlets, the square form preferably obtaining only immediately adjacent the inlets.

The invention and the foregoing and other features thereof will be understood more clearly and fully from the following detailed description with reference to the accompanying drawings in which:

Fig. 1 is a perspective view of a loud-speaker including a transducer constructed in accordance with this invention;

Figs. 2 and 3 are front and side views, respectively, of the transducer shown in Fig. 1; and

Fig. 4 is an end view of a coupler member for connecting the inlets or throats of alternate horns of the transducer.

Referring now to the drawings, the device therein shown comprises a plurality of horns 10 to 21, inclusive, disposed adjacent one another and arranged in three rows of four horns each. The horns 10 to 21 preferably are of substantially the same length and flare continuously from their inlets to their mouths or outlets, preferably so that the cross-sectional area of each of the passageways increases exponentially toward and to the mouth or outlet. The passageways in the horns are substantially identical and may be square in section at the inlet end and rectangular in section at all other points. Preferably the outlets or mouths of the several horns are disposed in a plane, adjacent edges of the mouths being substantially coincident as shown clearly in Fig. 2, and suitably secured together, for example by welding.

The outermost of the horns may be suitably secured, as by welding, to a rigid rectangular frame 22 having affixed thereto suitable rings or eyelets 23 by means of which the loud-speaker may be supported.

As shown clearly in Figs. 1 and 3, alternate horns in each of the horizontal rows and corresponding horns in the vertical rows are acoustically connected at their inlets or throats, as, for example, by coupler members 24. More specifically, referring particularly to Fig. 2, all of the even numbered horns are connected at their throats to one of the coupler members 24 and all of the odd numbered horns are similarly connected to the other of the coupler members 24. Metallic bands 30 may be provided to hold the throat portions of the horns of a group together.

As will be seen from Fig. 4, the coupler members 24 have circular inlets 26 and flare, preferably exponentially, to square outlets 27 in which the inlets or throats of the horns are fitted. Each of the coupler members has connected thereto a suitable receiver 25, which may be, for example, of the design disclosed in Patent 2,037,187 granted April 14, 1936 to Edward C. Wente. As a result of the flare and change in section of the passageways in each of the coupler members a smooth transition results between the outlets of the receivers 25 and the inlets or throats of the horns whereby distortion of the sound output of the receivers is prevented.

Because of the association of the various horns with the receivers as above described, the combined sound output of the two receivers will be distributed uniformly throughout a large space angle so that uniform quality and intensity of

speech and music will obtain throughout the sound field of the loud-speaker. This uniformity will obtain, it will be seen, even though one of the receivers should become inoperative.

5. Although in the specific embodiment shown in the drawings corresponding or vertically aligned horns are coupled to and receive energy from a common receiver, the various horns may be connected in other manners. For example, horns 10, 12, 15, 17, 18 and 28 may have their inlets or throats connected to one coupler member and the remaining horns may have their inlets or throats connected to another coupler member.

The various horns 10 to 21 may be fabricated 15 of sheet metal and may have the outer surfaces thereof covered with a vibration damping material. For example, sheets of roofing paper may be cemented to the walls of the horns to prevent vibration thereof. Also, if desired, the spaces 20 between the walls of the horns may be filled with a sound absorbing material, such, for example, as felt or cotton waste, to eliminate transmission of vibrations between the horns.

Although a specific embodiment of the invention has been shown and described, it will be understood, of course, that various modifications may be made therein without departing from the scope and spirit of this invention as defined in the appended claims.

30. What is claimed is:

1. An acoustic transducer comprising a multiplicity of horns disposed adjacent one another and each having an inlet and an outlet, and means acoustically coupling the inlets of only 35 alternate horns.

2. An acoustic transducer comprising a plurality of horns having inlets and outlets and each having therein a sound passageway flaring from the inlet to the outlet, the passageways in 40 said horns being of the same configuration and of substantially the same length, the outlets of said horns being adjacent one another, and means acoustically connecting only the inlets corresponding to alternate of said outlets.

45. 3. An acoustic device comprising a multiplicity of horns each having an inlet and an outlet, the outlets of said horns being arranged laterally adjacent one another in a row, means acoustically connecting the inlets corresponding to certain alternate of said outlets, and means separate from said first means acoustically connecting the inlets corresponding to other of said outlets.

4. An acoustic transducer comprising a plurality of similar horns having therein a passageway increasing in cross-sectional area from the inlet to the outlet thereof, the outlets of said horns being disposed in a plurality of rows and adjacent one another, and means acoustically connecting only the inlets corresponding to alternate outlets in said rows.

5. An acoustic device comprising a plurality of horns disposed in a plurality of equal rows and having their mouths laterally adjacent one another, means acoustically coupling only the

throats of corresponding alternate horns, and means acoustically coupling the throats of other of said horns.

6. An acoustic device comprising a plurality of horns of substantially equal length and of similar configuration, said horns being disposed in a plurality of equal rows, and having their mouths arranged in a plane, means acoustically connecting the throats of certain alternate horns in said rows, and means separate from said first means acoustically connecting the throats of other alternate horns in said rows.

7. An acoustic device comprising a pair of receivers, a pair of coupler members each connected to one of said receivers, a group of horns 15 having their throats connected to one of said coupler members, and a second group of horns having their throats connected to the other of said coupler members, said horns having their mouths disposed adjacent one another and the 20 mouths of the horns of one group being alternately arranged with the mouths of the horns of the other group.

8. An acoustic device comprising a group of horns arranged with their mouths in a plurality 25 of rows, means coupling the throats of said horns, a second group of horns arranged with their mouths in rows, and means acoustically separate from said first means coupling the throats of said second horns, at least one row of mouths of the horns in each group being disposed between two rows of mouths of the horns in the other group.

9. An acoustic device in accordance with claim 8 wherein the mouths of all of the horns are disposed in a plane.

10. An acoustic device comprising a pair of coupler members having square outlets, a pair of receivers each connected to the inlet of one of said coupler members, and a transducer comprising a plurality of horns having rectangular mouths and square throats, said horns being disposed in a plurality of equal rows, one group of corresponding alternate horns in said rows having their throats connected to the outlet of one of said coupler members, and the remainder of said horns having their throats connected to the other of said coupler members.

11. Sound reproducing apparatus comprising a plurality of groups of horns, portions of the horns of one group being interleaved with portions of the horns of another group, means acoustically coupling the inlets of only the horns in each of said groups, and a plurality of receivers each associated only with the horns of one of said groups.

12. An acoustic transducer comprising a plurality of groups of horns, each group comprising a plurality of horns, the horns of each group having a common inlet, the inlet of each group being acoustically separate from each other group, and the outlets of a portion of the horns of one group being interleaved with the outlets of a portion of the horns of another group.

FREDERICK R. MARION.
